WARE

ELECTRICAL FILTER SYSTEM

Application filed July 20, 1928. Serial No. 294,109.

The present invention relates generally to electrical filter systems, and more particularly filter systems used in connection with the energizing of vacuum tube amplifiers from alternating current or other sources of periodically fluctuating electrical energy.

A particular object of the invention is the effective filtration of fluctuating electrical energy employed in the energizing of vacuum tube amplifiers connected in cascade arrangements for the purpose of reducing hum disturbances where amplification of such disturbances is involved. A feature of the invention is the employment of apparatus having other useful functions in a composite system in the additional capacity of aiding in the desired effective filtration, an economical and constructional advantage of considerable importance.

20 The present popular demand for radio receivers insists upon an entire elimination of batteries for energizing the vacuum tube amplifiers used with such receivers with the result that the trend of production is towards 25 a design in which energizing of the tube is accomplished with energy originally derived from the usual commercially available alternating current and commutated direct current sources of supply, the designs involving 30 more or less elaborate filter systems and apparatus, the general features of which are well understood and recognized by the personnel of the art.

35 The features and advantages of the present invention are more fully outlined by reference to the figures of the accompanying drawings, like reference characters representing like parts in the several figures so far as possible.

40 Fig. 1 illustrates the invention in some of its phases employed in connection with current practice in radio receiver designs.

Fig. 2 illustrates suitable modifications in the arrangement of Fig. 1 in order to adapt 45 features of the invention to a common modification of radio receiver design.

Referring to Fig. 1 the radio receiver is shown to include a three-electrode vacuum tube VT₁ acting as a radio frequency amplifier, a vacuum tube VT₂ acting as a detector

and vacuum tube VT₃ and VT₄ acting as audio frequency amplifiers, the radio frequency input to the system being indicated as the source S₁ for example, a local oscillator, an antenna or loop system, or a telegraph line supplying a tunable circuit 1 through a radio frequency transformer RT₁. The radio frequency output of tube VT₁ is supplied to a tunable circuit 2 in the input circuit of detector tube VT₂ through a radio frequency 55 transformer RT₂. The detector output is supplied to tube VT₃ through audio frequency transformer AT₁ and thence to tube VT₄ through audio frequency transformer AT₂. The amplified output is transferred to a loud speaker or other translating device 60 LS through a choke AT₃ and condenser C₄ combination. This choke and condenser combination may be replaced by a two-winding 65 output transformer, an alternative common in practice, and illustrated in Fig. 2. The operation of the system outlined as a combination radio frequency amplifier, detector and audio frequency amplifier is too well known to require detailed explanation. 70

The filaments of tubes VT₁, VT₃ and VT₄ are indicated as heated by alternating current supplied through transformers ST₂ and ST₃, though they may be heated in any other suitable manner. The detector tube VT₂ is indicated in a conventional manner as an existing type having a cathode heated by a separate heating element by current supplied through transformer ST₁, this type of tube being quite general in current practice for 80 detector use in radio receivers energized from alternating current sources, though the present invention is not limited to any specific type of detector tube.

85 The plate electrodes in all of the tubes are shown energized from a common source S, which may be any source of direct current having periodically fluctuating components, such as commutated direct current or alternating current rectified and filtered in manners in common use, the polarities of the source being indicated by the + and - signs shown. Condenser C₅ indicates a part of the usual filter system employed in connection 90 with the use of fluctuating energy for energ- 100

gizing the plate circuits of amplifying tubes.

- The usual practice with apparatus currently available employs in the last stage of audio frequency amplification a more or less powerful tube in the position VT_4 , requiring higher potential of plate current than preceding tubes and correspondingly high potential for grid bias. The first audio amplifying tube VT_3 and the radio frequency amplifying tube VT_1 , and others if employed, are usually of the same type employing the same plate current energizing potential and grid bias potential, and are shown so connected in Fig. 1, the potential being less than that of tube VT_4 . The detector tube in position VT_2 generally employs the lowest plate energizing potential, is usually operated with little or no grid bias potential, and is shown so connected in the figure.
- The figure shows the output choke AT_3 of power tube VT_4 connected directly to the positive terminal of source S , the usual design providing for the source S producing approximately the desired operating potential for this tube. The primary windings of audio frequency transformer AT_2 and radio frequency transformer RT_2 are shown connected to the positive side of source S through a resistance R_6 , which resistance is chosen of such value as to produce a desired reduction of potential in the over-all potential of source S to suit the operating requirements of the particular tubes as amplifiers, and in usual practice may effect a reduction from the neighborhood of 200 or more volts to the neighborhood of from 90 to 150 volts. Condenser C_6 shunted across the reduced potential acts to by-pass signaling currents to the negative side of the source S , is a low impedance to reduce feed-back effects between the tubes, and serves the additional function of further filtering the fluctuating current supplied to the plates of these amplifying tubes. For these reasons this condenser is chosen of rather large value, such as from 1 to 2 microfarads where the periodic fluctuations of the supply energy are in the neighborhood of 60 cycles per second.

The primary winding of audio frequency transformer AT_1 is connected to the plate side of the output circuit of tube VT_3 through a resistance R_7 of suitable value and the arm of a switch SW placed upon the lower contact thereof, to further lower the supply potential to suit the operating requirements of tube VT_2 as a detector. A condenser C_7 is connected across this reduced potential to the negative side of the source S for the same purposes as condenser C_6 , and is also of rather large value for the same reasons given in connection with condenser C_6 .

Since the fluctuating component of the supply energy in the plate circuit of detector tube VT_2 is twice amplified by tubes VT_3

and VT_4 , and the audio frequency transformers AT_1 and AT_2 are efficient transfer elements for the frequencies of generally available commercial sources of supply, it is obvious that hum producing currents arising in the detector stage may become quite substantial in magnitude on arrival in the output circuit of tube VT_4 . For this reason, it is highly desirable that fluctuating energy supplying tube VT_2 be smoothed out to a high degree, and much more so than is required in connection with tube VT_3 and tube VT_4 . That is, the filtering should be more perfect in proportion to the amplification that follows the tube in which the fluctuating energizing current is being used. By so connecting the supply to the plate of tube VT_2 that the supply current first passes through primary winding of audio frequency transformer AT_2 , there is obtained an additional filtering action cooperating with the filtering action of resistance R_7 and condenser C_7 , so that the primary winding of audio frequency transformer AT_2 serves the double function of transferring signal current energy and filtering detector tube supply current energy.

It is pointed out that this proportioning of the filtering from stage to stage in an audio frequency amplifying system in consideration of the degrees of amplification that the hum disturbances are subjected to is of great importance, particularly in an arrangement where advantage is taken of so-called stage-to-stage bucking; that is, using the hum disturbances created in one stage to oppose or neutralize the hum disturbances created in other stages, as by properly phasing the windings of the audio frequency transformers to pass the hum from one stage to another in the desired opposing phase. These latter features are not claimed herein as original with me, being the invention of another, but the provision I make for using apparatus already a part of the amplifying system for arriving at a high order of filtration for early stages of such a system is of particular value in reducing the cost and complications of arrangements necessary to such systems.

In the event that there is not a substantial difference between the plate potential required for the detector tube and the plate potential required for the first audio tube, the resistance R_7 would be of relatively small value. By reason of its connection it is a shunt to the primary of audio frequency transformer AT_2 , so that a small value of resistance would act to divert a large amount of signal energy from the transformer, resulting in undue inefficiency. In a case of this kind, or for other reasons, it may be desirable to connect the resistance to the plate side of the second audio frequency tube, using a large resistance R'_7 , by moving the arm of the switch SW to its upper con-

- tact, as in most cases there is a substantial difference between the detector tube plate potential and the output tube plate potential. As before the detector tube plate current would have the benefit of the filtering action of choke coil AT_3 , or the primary winding of the output transformer if such is used in lieu of the choke coil and condenser combination for coupling the loud speaker.
- 10 In some cases to avoid excessive feed-back effects between tubes interlinked by a connection such as described it is desirable to bypass a part of the potential reducing resistance, a feature shown in connection with resistance R'_7 where the condenser C'_7 connects an intermediate point of this resistance to the negative side of source S. In such case it is usually possible to use less capacity in condenser C_7 as condenser C'_7 has a useful filter effect on the detector plate current in the position shown. The feed-back effects referred to may cause so-called "motor-boating" if excessive, or may cause either regenerative amplification to undesirable degree or loss of amplification by degeneration depending upon whether the connections are such as to feed-back in aiding phase or opposing phase, a matter depending upon the way the windings of the audio frequency transformers are connected in the system in the matter of polarity.
- 15 Obviously, better filtration of the plate current supplied to the first audio tube VT_3 could be had by connecting the supply lead to the plate side of tube VT_4 instead of directly to the positive side of source S as shown, and other combinations of connections to take advantage of my invention are possible, depending upon the particular design of system.
- 20 I have shown resistances R_2 and R_3 connected for obtaining grid bias potentials for the amplifying tubes, these resistances being shunted by by-pass condensers C_2 and C_3 respectively, which features are common practice and require no particular explanation. These resistances are connected to the filaments of the tubes through potentiometer P_2 and P_3 respectively, also common practice
- 25 requiring no explanation. Of course other means for obtaining grid bias potentials for operating the tubes as amplifiers may be substituted, these features not being peculiar to my invention.
- 30 In Fig. 2 a modification of the amplifying system of Fig. 1 is shown, this being the use of a so-called push-pull arrangement in the output stage of the system comprising the two output tubes VT'_4 and VT''_4 . In this arrangement I have provided a resistance R_9 in shunt to the primary of output transformer AT_3 , and connected the supply lead to the plate circuit of detector tube VT_2 to the approximate midpoint of this resistance through a switch SW' , the arm of which is
- 35 placed upon the upper contact thereof, this in order to maintain the required balance in the push-pull system. This resistance should be large in order to keep low the short-circuiting effect on the primary of audio frequency transformer AT_3 . I have shown an additional resistance R'_7 in series with the supply circuit, but this may be eliminated and all of the resistance needed for reducing the detector plate circuit potential to the required value may be included in the resistance element R_9 . Obviously the plate current supply for detector tube VT_2 is subjected to the filtration effect of the primary winding of output transformer AT_3 , as well as the filtration effect of resistance R_9 , resistance R_7 if used and condenser C_7 . The detector tube may have its plate current supply derived from a connection to the plate side of tube VT_3 , by movement of the arm of switch SW' to the lower contact thereof, as in the case of Fig. 1, and the tube VT_3 may have its plate current supply derived from the output side of the push-pull tubes by way of resistance R_9 , by shifting the arm of switch SW'' to its lower contact, or other modification made to take advantage of the benefits of my invention.
- 40 I have shown the filament system of tubes VT'_4 and VT''_4 connected to the approximate mid-point of the secondary winding of audio frequency transformer AT_2 through a resistance R_8 , which may be shunted by an audio frequency signal current by-passing condenser C_8 , and the plates of these tubes connected to the positive side of the source S through a choke CH , this being one procedure for breaking up a tendency on the part of a push-pull connection such as shown from oscillating by reason of feed-back effects inherent to a push-pull connection.
- 45 For energizing the plate circuit of amplifying tube VT_3 I have shown a connection from the primary winding of audio frequency transformer AT_2 by way of resistance R_6 and the switch SW'' , when the arm thereof is moved to its upper contact to the positive side of source S through choke coil CH , this in order to employ the filtering action of this choke if needed in connection with the action of tube VT_3 in the system, thus giving to this choke an additional function. As before the resistance R_6 provides for reducing the potential the desired amount to satisfy the operating requirements of tube VT_3 , and the condenser C_6 acts both as a by-pass condenser for signal currents and an aid to filtering.
- 50 I have found that by using the elements pointed out by me in various ways as aids to filtering I have been able to make substantial reductions in hum produced when energizing such systems as I have described with fluctuating energy derived from the usual 60 cycle alternating current commercial sources

of supply, employing the usual rectifying and filtering devices for converting the raw alternating current into pulsating unidirectional current.

5 While I have particularly described my invention in connection with radio receiving apparatus of popular form, no limitations are intended by reason of such selection, the invention being one of general application.

10 Having fully described my invention I claim:

1. In a system for the successive amplification of alternating current, the combination of a plurality of multi-electrode electron discharge tubes connected in cascade, impedance signal-transfer means in the output circuits of said tubes, a common source of fluctuating uni-directional current for energizing the anodes of said tubes, and a filter-effective combination of impedances associated with at least two tubes of the system, said combination including as filter-effective elements the impedance-transfer elements in series connection for the transmission with filter effect therethrough of the anode current for a preceding tube from the output circuit of a succeeding tube.

2. In a system for the successive amplification of alternating current, the combination of a plurality of multi-electrode electron discharge tubes connected in cascade, impedance signal-transfer means in the output circuits of said tubes, a common source of fluctuating uni-directional current for energizing the anodes of said tubes, and a filter-effective combination of impedances associated with at least two tubes of the system, said combination including as filter-effective elements the impedance transfer elements in series connection for the transmission with filter effect therethrough of the anode current for a preceding tube from the output circuit of a succeeding tube and an additional filter-effective element comprising a condenser connected at one side to the negative side of said common source, and at the other side between said series connected transfer elements.

3. In a system for the successive amplification of audio frequency current the combination of a plurality of three electrode vacuum tubes, audio frequency transformers linking said tubes in cascade relation, an output transformer, a common source of fluctuating uni-directional current and connections for energizing the output electrodes of said tubes, connections whereby the energizing current is positively supplied to the output electrode of a preceding tube after passing through the primary winding of the transformer in the output circuit of a succeeding tube, and a condenser of low impedance to audio frequency current linking said connection to the negative side of said source.

4. In a system for the successive amplification of alternating currents the combination

of a plurality of three electrode vacuum tubes, impedance means linking said tubes in cascade relation, an output impedance means within the output circuit of the last tube of said cascade a common source of fluctuating 70 uni-directional current and connections for energizing the output electrodes of said tubes, and means for supplying the output electrode of a preceding tube with positive current of substantially lesser potential than the potential of said source and a higher order of filtration than had in the current supplied to succeeding tubes comprising a circuit including an energy consuming device connected to the output electrode of said preceding tube 80 and to the positive side of said source through the impedance means in the output circuit of a succeeding tube, and a condenser linking the positive side of said energy consuming device to the negative side of said source. 85

5. In a system for receiving and amplifying high frequency modulated currents including a three electrode vacuum tube for detection followed by one or more tubes, including an output tube for audio frequency amplification, impedance means in the output circuits of said tubes for transferring audio frequency current energy from one tube to the next, an output impedance means within the output circuit of said output tube, a common source of fluctuating uni-directional current for energizing the output electrodes of said tubes, a connection for positively energizing the output electrode of said detector tube including means therein for reducing the potential of said source, said connection having included therein the impedance means in the output circuit of one of said audio frequency amplifying tubes, and a condenser linking the output electrode of said detector 100 tube to the negative side of said source. 105

6. In a system for the successive amplification of alternating currents the combination of a plurality of three electrode vacuum tubes, audio frequency impedance means linking said tubes for cascade amplification, two of said tubes being connected in push-pull relation as a single stage of amplification and preceded by one or more tubes in series relation to said push-pull stage, an output impedance means within the output circuits of said tubes arranged in push-pull relation, a common source of fluctuating uni-directional current and connections for energizing the output electrodes of said tubes, a resistance connecting the output electrodes of the tubes of said push-pull stage, a connection to the output electrode of a preceding tube from an approximate midpoint of said resistance, and a condenser linking said connection to the negative side of said source. 115 120

7. In a system for the successive amplification of alternating current the combination of a plurality of three electrode vacuum tubes including an output tube, inductive imped- 125 130

ance means in the output circuits of said tubes for transferring energy of said currents from one tube to another, an output impedance means within the output circuit of said output tube, a common source of fluctuating unidirectional current and connections for energizing the output electrodes of said tubes, one of said connections leading to the output electrode of a preceding tube by way of one of said inductive impedance means in the output circuit of a succeeding tube, a resistance in said connection, a condenser linking an intermediate point of said resistance to the negative side of said source, and a second condenser linking the output electrode of said preceding tube to the negative side of said source.

In testimony whereof I affix my signature.
